WINDOW OPERATOR

Anton Rappi, Buffalo, and Erwin C. Horton, Hamburg, N. Y., assignors to Trico Products Corporation, Buffalo, N. Y.

Original application September 17, 1940, Serial No. 357,140. Divided and this application September 10, 1941, Serial No. 410,288

8 Claims. (Cl. 268—125)

This invention relates to an operating mechanism for the windows and other closures of motor vehicles, and more particularly to the fluid pressure type of operator. This application is a division of application Serial No. 357,140, filed September 17, 1940.

It has heretofore been proposed to open and close the windows of automobiles by means of a fluid pressure motor comprising a relatively long chamber or cylinder having an extensible piston-like member for rocking a window actuating lever, the cylinder being pivotally mounted at one end and having its free end, from which the piston-like member projects, free to swing in accommodation of the movement incidental to the rocking of the lever.

The present invention has for its object to provide an improved mounting for the fluid motor by which the operation of the latter is rendered more efficient and practical.

The invention further has for its object to provide an improved mounting for the motor cylinder by which the swinging or oscillating movement of the cylinder is guided in a practical manner for steadyng the moving parts and avoiding unnecessary operational noises.

In the accompanying drawing

Fig. 1 is a phantom view of a portion of an automobile door showing the present invention incorporated therein;

Fig. 2 is an end elevation thereof showing the free end of the cylinder with its guiding support;

Fig. 3 is fragmentary side elevation of the free end of the cylinder; and

Fig. 4 is a detailed view more clearly showing the pivotal mounting for the cylinder.

Referring more particularly to the drawing, the improved mechanism has been depicted in connection with the vertically sliding type of closure or window for the sake of illustration. This window is designated by the numeral 1 which is guided vertically in channel ways 2 on the door 3.

The window glass is elevated by means of a fluid motor, preferably one utilizing an air pressure differential in which the low pressure influence of the intake manifold may be used. As illustrated, the motor comprises a cylinder 4 and a piston 5. The piston rod 6 is operatively connected to the window to elevate and lower the same as desired. The connection disclosed embodies a bell crank lever 7 pivoted on a stud 8 carried by a bracket 9, and to this stud is fixed one end of a convolute spring 10 to counterbalance the sash, the opposite end of the spring being fixed to the sash connected arm of the bell

crank. The cylinder is yieldably mounted on a support bracket or track part 11 through a bracket or roller part 13 and a tension and compression member 12 in the form of a spring leaf. The arrangement providing in effect a Z-shaped support wherein the parts are in substantially stacked relationship. This mounting permits the opposite end of the cylinder with its protruding piston rod to swing in a vertical plane for accommodating the arcuate travel of the pivotal connection 14 between the free end of the piston rod and the other arm of the bell crank lever incidental to the sliding motion of the piston. A steadyng influence is exerted on the outer end of the cylinder during this swinging movement by a fixed guide finger 15 which works in a slot or guideway 16 of the cylinder head 11.

The track part 11 and the roller part 13 are given a slight curvature so that during the pivotal movement of the cylinder 4 the motor carried roller part 13 will roll back and forth on the spring leaf. This provides a free and rolling mounting for the motor, and any incidental shift of the motor by reason of this rolling action will be accommodated by the slot 16 as it rises and falls on the guide finger 15.

By reason of the guiding finger or support 15 the cylinder will be restricted in its oscillatory motion to a constant plane and held against lateral play which unguided lateral play would cause sidewise stress on the piston rod and the bell crank lever.

The foregoing description has been given in detail for the sake of clarity. It is obvious that the inventive principles herein involved may be incorporated in other physical embodiments without departing from the spirit or scope of the claimed invention.

What is claimed is:

40. 1. Operating mechanism for the closures of vehicles, and the like, comprising a fluid motor having an elongated chamber with a fluid actuated rod slidably guided through a bearing in one end thereof, power transmission means including
45. a lever pivotally connected to the outer end of the rod, said one end of the chamber being free to swing to accommodate the arcuate travel of the point of pivotal connection between the rod and lever, means pivotally mounting the opposite end of the chamber, the first end of the chamber having a transverse slot, and a guiding finger slidably received in the slot, said transverse slot being formed in an integral part of the rod bearing adjacent the rod whereby guiding support of the rod, piston and cylinder assem-

bly is provided substantially midway of the assembly when the rod is in its extended position and close to the longitudinal axis of the assembly to reduce vibration and torque to a minimum.

2. Operating mechanism for the closures of vehicles, and the like, comprising a fluid motor having an elongated chamber with a fluid actuated rod slidably guided through one end thereof, power transmission means including a lever pivotally connected to the outer end of the rod, said one end of the chamber being free to swing to accommodate the arcuate travel of the point of pivotal connection between the rod and lever, a supporting bracket for mounting the opposite end of the chamber, a bracket part fixed on said opposite end of the chamber and overlying the bracket, and an intermediate spring leaf fixed at one end to the bracket and at the opposite end to the bracket part whereby said bracket, said bracket part and said spring leaf are in substantial stacked relationship.

3. Operating mechanism for the closures of vehicles, and the like, comprising a fluid motor having an elongated chamber with a fluid actuated rod slidably guided through one end thereof, power transmission means including a lever pivotally connected to the outer end of the rod, said one end of the chamber being free to swing to accommodate the arcuate travel of the point of pivotal connection between the rod and lever, a supporting bracket for mounting the opposite end of the chamber, a bracket part fixed on said opposite end of the chamber and overlying the bracket, and a spring leaf fixed at one end to the bracket and at the opposite end to the bracket part, the bracket part being curved to rock upon the bracket.

4. Operating mechanism for the closures of vehicles, and the like, comprising a fluid motor having an elongated chamber with a fluid actuated rod slidably guided through one end thereof, power transmission means including a lever pivotally connected to the outer end of the rod, said one end of the chamber being free to swing to accommodate the arcuate travel of the point of pivotal connection between the rod and lever, means guidingly supporting said one end of the chamber against lateral movement during its swinging motion, and means mounting the opposite end of the chamber for such swinging movement, said last means comprising a support having a track part, a roller part on said opposite end of the cylinder mounted on said track part for longitudinal movement thereon during swinging motion of the cylinder, and a member connecting the roller part to the track part for holding such parts operative.

5. Operating mechanism for the closures of vehicles, and the like, comprising a fluid motor having an elongated chamber with a fluid actuated

rod slidably guided through one end thereof, power transmission means including a lever pivotally connected to the outer end of the rod, said one end of the chamber being free to swing to accommodate the arcuate travel of the point of pivotal connection between the rod and lever, means guidingly supporting said one end of the chamber during its swinging motion, and means mounting the opposite end of the chamber, said last means comprising a support having a track part, a part on said opposite end of the cylinder rollingly mounted on said track part for longitudinal movement thereon during swinging motion of the cylinder, and a tension and compression member connecting said cylinder part to the track part for holding such parts operative.

6. Closure operating mechanism comprising a fluid motor having a piston and cylinder, means guidingly supporting the cylinder at one end against lateral sway and body torque while allowing for vertical swinging and bodily motion in a constant longitudinal plane, and a substantially Z-shaped support mounting the cylinder at its opposite end, the angular bar of the Z-shaped support being of a resilient nature.

7. Window operating mechanism adapted for automotive installation, comprising, a fluid motor having a cylinder and a piston therein with a rod extending therefrom, means at one end of said cylinder for mounting it upon a fixed member, said means permitting swinging of said cylinder and bodily longitudinal movement thereof during actuation of said fluid motor, an operative connection between said piston and a window including a lever pivoted to the piston rod, the other end of said cylinder having a slotted guideway adjacent the egress opening in the cylinder head for said piston rod, and a fixed guide slidably embraced by said guideway for maintaining said fluid motor in a constant plane of operation during such swinging and bodily longitudinal movement as it rocks the lever to actuate the companion window.

8. Closure operating mechanism adapted for installation in the narrow well of an automobile window structure, comprising a fluid motor having a cylinder and piston, an operative connection between said closure and said motor, a mounting for said motor having a flexible member and connecting said motor to said window structure while normally allowing bodily swinging and shifting of said motor in various directions, and guide means for restricting the flexure of said flexible member to a constant plane substantially parallel to the walls of said window well whereby said mechanism will be restrained from contact with said walls.
